UNITED STATES PATENT OFFICE.

PRISCILLA E. WEBBER, OF LYNCHBURG, VIRGINIA.

DESIGN FOR A DRINKING-GLASS COASTER.

Application filed March 1, 1928. Serial No. 25,629. Term of patent 14 years.

To all whom it may concern:

Be it known that I, PRISCILLA E. WEBBER, a citizen of the United States, residing at Lynchburg, in the county of Campbell and State of Virginia, have invented a new, original, and ornamental Design for Drinking-Glass Coasters, of which the following is a specification, reference being had to the accompanying drawing, forming part thereof.

Figure 1 is a top plan view of a drinking glass coaster, showing my new design, and

Figure 2 is a longitudinal sectional view taken through the center of the coaster.

The article is used to support a drinking glass on a table to prevent condensed moisture from running down the glass onto the table.

I claim:

The ornamental design for a drinking glass coaster, as shown and described.

PRISCILLA E. WEBBER.
